CHEST

Seely F. Pratt, Le Roy, N. Y., assignor to The
Union Steel Chest Corporation, Le Roy, N. Y., a
corporation of New York

Application July 17, 1933, Serial No. 680,877

15 Claims. (Cl. 206—16)

This invention relates to chests or containers.

One object of the invention is to provide a relatively small metal or other chest or container provided with a tray operatively connected with the chest and the cover thereof for automatic swinging movement with the cover and maintained always in a horizontal plane and readily applied and disconnected from the chest or container.

Another object resides in the provision of a tray for chests or other containers constructed for movable mounting in the chest without interference with movements of the cover of the chest and which may be easily and readily removed from the chest if desired for use independently of the chest and so constructed that it may be employed for various purposes on counters, desks or the like without danger of accidental upsetting.

A still further object of the invention is to provide a chest having a tray so constructed that the tray may be readily supported within the chest for swinging movement with relation to the cover of the chest or supported on the body of the chest independently of a connection with the cover so as to have a slidable movement on the upper edges of the body under the cover of the chest without interference with the movements of the cover of the chest.

It is still further designed to provide a chest having a hinged cover with a tray swingingly connected with the chest and the cover, the arrangement being such as to provide for engagement of the tray with the rear wall of the chest to limit the outward swinging movement of the cover with relation to the chest.

With these and other objects in view, the invention consists in the construction and novel combination and arrangement of parts herein-after fully described, illustrated in the accompanying drawings, and set forth in the claims hereto appended, it being understood that various changes in the form, proportion and minor details of construction, within the scope of the claims, may be resorted to without departing from the spirit of the invention or sacrificing any of the advantages thereof.

In the drawings:

Figure 1 is a top plan view of the invention partly broken away to show the interior of the chest with the tray swingingly supported therein.

Fig. 2 is a transverse sectional view on the line 2—2 of Fig. 1.

Fig. 3 is a longitudinal sectional view through

the body of the chest showing the cover elevated and the tray lifted out of the body of the chest.

Fig. 4 is a transverse sectional view on the line 4—4 of Fig. 3.

Fig. 5 is an enlarged detail fragmentary view showing one form of means for swingingly mounting the tray with relation to the chest.

Fig. 6 is a detail fragmentary sectional view illustrating one of the pivotal or trunnion connections between one end of the tray and one end of the cover of the chest.

Fig. 7 is a detail fragmentary view illustrating a modified form of lever connection between the body of the chest and the tray.

Fig. 8 is a side elevation of a chest showing another form of lever connection between the body of the chest and the tray.

Fig. 9 is a detail fragmentary top plan view of the invention, illustrating the tray mounted for sliding movement on the body of the chest independent of any lever connection with the cover.

Fig. 10 is a fragmentary detail sectional view on the line 10—10 of Fig. 9.

Fig. 11 is a transverse sectional view through the tray illustrating the tray mounted on a table, counter or the like independently of association with the chest.

Referring now more particularly to the accompanying drawings, the reference character A indicates the body of a chest or container provided with a cover B between which is detachably connected a swinging and removable tray C.

The body A of the chest may be composed of any suitable material, but it is preferably formed of thin sheet metal including front and rear walls 1 and 2 respectively and end walls 3. The upper edges of the front, rear and end walls are inwardly offset as at a forming a continuous shoulder 4 upon which the front and rear flanges 5 and 6, respectively, and the end flanges 7 of the cover B may rest when the cover is closed and whereby in the closed position of the cover the flanges of the cover lie in the vertical plane of the vertical walls of the body A.

The cover B is composed preferably of thin sheet metal and is hinged to the rear wall of the body A in any suitable manner. One hinge means may reside in the use of a hinge pintle 8 which passes through curled portions 8' of the rear flange of the cover and through curled portions 8^a of the hinge members 8^b, spot welded or otherwise secured to the inner face of the rear wall of the body of the chest. If desired, the cover may be provided with a handle 9 having its inner ends journaled in the bearings 10 (Fig. 3) of the

cover B so that when the cover is locked or fastened to the body in any suitable manner the chest or container may be readily and conveniently carried or transported from one place to another. A

5 suitable locking means 11-12 may be associated with the chest and a specific description of the same is deemed unnecessary in this application.

The tray C is preferably semi-cylindrical in cross section and has substantially segmental shaped ends 13 provided at their upper edges with overhanging flanges 14 having their outer edges turned downwardly as at 15 for a purpose presently explained, with the lower portions of the ends 13 having depending leg portions 16 terminating at their lower ends with laterally inwardly directed portions 17 forming feet whereby the tray may be supported in steady or firm position when disconnected from the chest, as will be later explained, or to engage the upper edge of 10 the inwardly inset portion *a* of the rear wall of the chest when the cover B is elevated. The feet 17 of the legs 16 of the tray perform the function of stops in that when the cover B is swung upwardly and slightly rearwardly the tray is brought 15 to a position where the feet 17 of the legs 16 stop further rearward movement of the cover. Therefore, when the cover B is elevated to permit 20 access to the chest or to the tray, as will be later explained, the tray is maintained in horizontal 25 position as shown in Fig. 4, and the cover is arrested in its rearward movement by engagement of the feet 17 of the legs 16 of the tray with the rear wall of the chest, as just alluded to.

To swingingly connect the tray to the cover and 30 to the body of the chest and to maintain the tray normally in horizontal position and to provide for the aforesaid limiting of the movement of the cover B by the tray, the tray is provided in each end with an aperture 18 adapted to receive trunnions 19 projecting from the ends of the cover B. These trunnions 19 are laterally directed from the flat portions 19' from which these trunnions are formed and the flat portions 19' are secured 35 to the inner faces of the ends of the cover by soldering, spot welding, or otherwise. The ends of the cover B being more or less flexible, these trunnions 19 may be sprung into and out of the perforations 18 at the rear sides of the end pieces 13 of the tray, and the trunnions 19 have spaced 40 stops 19^a which are swedged out of the metal of which the trunnions are formed to provide stops calculated to maintain positive clearance inside 45 the cover for the tray. Each end piece of the tray also has a perforation 20 adjacent the front 50 of the tray which is adapted to receive the laterally directed outer ends 21 of the levers 22, one at each end of the chest and which are of peculiar formation and are detachably seated at 55 their inner ends in apertures 23 in the end walls 60 of the body A of the chest. By reason of this link or lever connection 22-22 between the body A of the chest and the tray at each end thereof, the tray swings relatively to the swinging of the cover B into and out of the body A of the chest 65 and always in a horizontal position so that articles or materials carried by the tray are not dislodged from the tray as the cover is opened and closed, there being sufficient clearance between the ends of the tray and the ends of the body A to 70 permit the tray to be swung into and out of the body A of the chest. The ends of the tray are embossed outwardly slightly in a tapered formation as at 24 to take up or prevent play between the tray ends and the ends of the body A when the tray is mounted loosely on the upper edges of

the inwardly set portions *a* of the ends of the body A and which may be the position of the tray at times if desired, as will be hereinafter explained.

In the preferred form of the invention the levers 22 arranged one at each end of the chest, are composed preferably of wire material and are resilient or yieldable, and as shown in the preferred form of the invention, as disclosed in Figs. 1 to 6, inclusive, these levers 22 are threaded or passed through the apertures 20 of the tray and the apertures 23 of the body A from the inside of the tray and the body. To this end the levers 22 have their inner or lower ends deflected as at 24' in rounded formation and deflected as at 25 to form a shoulder 26. The outer or upper end of each lever 22 has a head 27 formed at the outer end of the laterally directed portion 21. To thread or insert the levers from the inside of the body A and from the inside of the tray, these levers have their hooked inner or lower ends passed first through the apertures 20 of the tray and then the rounded lateral extensions 24 are passed through the apertures 23 of the body A to position the shoulders 26 of the levers 22 with 90 relation to the perforations 23 in the body of the chest, the heads 27 of the levers 22 lying against the inner faces of the ends of the tray as shown particularly in Fig. 5. The levers 22 are slightly 95 bent intermediate their ends as shown in Fig. 5 100 so as to provide for clearance between the levers 22 and the ends of the tray and the body A so as to prevent binding of the parts in the swinging movement of the cover and the tray with relation 105 to the body A.

In another form of the invention the levers 22 may be threaded or inserted from the outside of the body A and the tray, as shown in Fig. 7, wherein the levers 22' have laterally directed ends 28 forming journals which are adapted to be sprung 115 into the perforations 20' corresponding to the aforesaid perforations 20. The levers 22' are bent as in the case of the levers 22 and at the inner or lower ends of the levers 22 they are directed laterally as at 29 and headed as at 30. To insert 120 these levers 22 from the outside of the body A and from the outside of the tray, the laterally directed ends 28 are first passed through the apertures 23' in the body A, and the levers directed upwardly to the perforations of the ends of the tray, while the 125 heads 30 of the levers bear against the ends of the body A. In either form of levers 22-22' there is a spring action of the unheaded ends of the levers in their respective perforations, and this is provided by the resiliency or yieldability of the 130 sheet metal of which the body and tray are formed, as well as the resiliency of the levers.

In another form of the invention, the levers may be formed as shown at 31 in Fig. 8, wherein the upper or outer ends of the levers 31 may be formed the same as shown in Fig. 7 and the headed lower or inner ends 32 of the levers 31 may operate in the bayonet slots 33, one in each end of the body A of the chest.

In the use of any one of the forms of levers 22, 22' or 31, illustrated, the tray C is adapted to swing with the cover B and always maintained in a horizontal plane to prevent dislodging of contents of the tray, and in each instance the feet 17 of the legs 16 of the tray are adapted to engage the upper edge of the rear wall of the body of the chest and to positively limit rearward movement of the cover and by virtue of which, when the cover is thrown to the limit of its outward movement, 150

the feet 17 of the tray legs 16 rest directly upon the inset portion *a* of the rear wall of the body portion of the chest.

There are times when the tray is desired to be used separately from the chest, and in such a case, the tray may be readily removed from its pivotal connections from the body A and the cover B, as should now be well understood.

After the tray has been disconnected from the body A and the cover B it might be desired to use the tray within the chest, but without the swinging movement. To this end the flanges 14 at the ends of the tray may be seated upon the upper edge of the ends of the body A for a sliding movement of the tray transversely of the body to any point between the front and rear walls of the body A. The downwardly turned edges 15 of the flanges 14 cooperate with the outwardly bulged or embossed portions 24 to take up or prevent undue play between the tray ends and the ends of the body of the chest when the tray is used as a loose tray, for this said sliding movement of the same on the body A. There may be times when it is desired to use the tray entirely independently of the chest. For instance, it may be desired to use the tray for containing articles or materials without the use of the chest at all. The tray is highly serviceable for use by cashiers or others on desks or counters, and in such use the tray is highly serviceable and not liable to accidental upsetting by virtue of the employment of the relatively large feet 17 on the legs 16 of the tray, and by virtue of which the tray may be adequately supported on a desk, table, or the like.

The tray may be of other form than that illustrated, and it may or may not have partition members in it, but as shown, the tray is preferably divided up into a plurality of compartments by means of partitions 34 which may be segmental in formation to correspond with the cross sectional form of the tray, and which are adapted to be seated in grooves 35 pressed or otherwise formed in the bottom and front and rear walls of the tray, and held therein by means of notches 36 formed in the lower edges of the partition 34 and adapted to be sprung over protuberances 37 projecting inwardly of the tray adjacent the ends of the grooves 35, and all grooves, protuberances and partitions being formed alike, they are readily interchangeable and some partitions may be omitted to vary the size of the compartments in the tray if partitions are used.

From the foregoing it will be seen that I provide a relatively simple, inexpensive, durable and effective chest for the storage and transportation of articles or materials and that the tray may be swingingly or slidably mounted with relation to the chest, or entirely removed therefrom and used for purposes aside from general use of the chest. If desired, the exterior of the cover may be provided with graduations *b* and the interior thereof provided with graduations *c*, for measuring purposes.

What is claimed is:

1. A chest comprising a body and a cover hinged to the body at the back thereof and provided with marginal flanges, and a tray extending longitudinally of the chest and pivoted at its ends adjacent the rear wall to the end flanges of the cover, and levers pivotally mounted on the end walls of the chest and pivotally connected to the end walls of the tray and adapted to maintain the tray in a horizontal position throughout the opening and closing movements of the cover, the said tray having feet arranged to engage and

rest upon the back wall of the body of the chest to limit the opening movement of the cover.

2. A chest comprising a body and a cover hinged to the body at the back thereof and provided with marginal flanges, and a tray extending longitudinally of the chest and pivoted at its ends adjacent the rear wall to the end flanges of the cover, and levers pivotally mounted on the end walls of the chest and pivotally connected to the end walls of the tray and adapted to maintain the tray in a horizontal position throughout the opening and closing movements of the cover, said levers being resilient and bent intermediate their ends and having detachable connection with the body of the chest and tray.

3. A chest comprising a body and a cover hinged to the body at the back thereof, and a tray pivotally connected to the body and to the cover for swinging movement with the latter and having projecting portions engageable with the rear wall of the body to limit the opening swinging movement of the cover.

4. A chest comprising a body and a cover hinged to the body at the back thereof, and a tray pivotally connected to the body and to the cover for swinging movement with the latter and having downwardly projecting legs provided with laterally directed feet adapted to swing into engagement with the rear wall of the chest as the cover is opened so as to thereby limit the opening movement of the cover.

5. A chest comprising a body and a cover hinged to the body at the back thereof, and a tray pivotally connected to the body and to the cover for swinging movement into and out of the body as the cover is swinging in opposite directions to open and close the chest, the tray having flanges at its ends which overlie the ends of the body when the cover is in closed position and also having projecting portions for engagement with the rear wall of the chest to limit the outward swinging movement of the cover.

6. A chest comprising a body and a cover hingedly connected thereto, and a tray disposed in the body and having flanges at its ends for engagement with the upper edges of the end walls of the body for sliding movement transversely of the body between the front and rear walls thereof on the ends of the body, the ends of the tray having outwardly bulged portions for engagement with the inner faces of the ends of the body to prevent undue longitudinal play of the tray with relation to the body.

7. A chest comprising a body and a hinged cover therefor, the cover having a trunnion at each end, and a tray having a perforation at each end adapted to be sprung over said trunnions whereby to pivotally connect the tray to the cover, levers pivotally connected to the body and to the tray to effect swinging movement of the tray with the cover so as to swing the tray into and out of the body and to maintain the tray in horizontal position whether in or out of the body, and means carried by the tray for engagement with the rear wall of the body to limit the outward swinging movement of the cover.

8. A chest comprising a body, and a tray including a body substantially semi-circular in cross section and of less width than said chest body and at its ends having flanges adapted to rest slidably upon the upper edges of the end walls of the chest for backward and forward movement transversely of the body on the upper edges of the ends of the latter.

9. A chest comprising a body, and a tray in-

- cluding a body substantially semi-circular in cross section and of less width than said chest body and at its ends having flanges adapted to rest slidably upon the upper edges of the end walls of the chest for backward and forward movement transversely of the body on the upper edges of the said flanges of the ends of the body, the outer edges of the flanges being directed downwardly. 5
10. A chest comprising a body, and a tray including a body substantially semi-circular in cross section and at its ends having flanges adapted to rest upon the upper edges of the end walls of the chest, the outer edges of the flanges being directed downwardly, and the ends of the tray below said flanges having outwardly directed projecting portions to lie adjacent the inner faces of the body to coact with the said flanges and their downwardly turned edges to prevent undue longitudinal play of the tray relative to the body of the chest. 15
11. A chest comprising a body and a hinged cover therefor, a tray, means for pivotally and detachably connecting the tray to the body and to the cover, the tray having flanges at its ends to rest upon the end walls of the body upon disconnection of said detachable means, and means carried by the tray to engage the rear wall of the body to limit the outward swinging movement of the cover. 20
12. A chest comprising a body and a hinged cover therefor, a tray, means for pivotally and detachably connecting the tray to the body and to the cover, the tray having flanges at its ends to rest upon the end walls of the body upon disconnection of said detachable means, and legs depending from the ends of the tray and having feet adapted to rest on the rear wall of the body to limit the outward swing of the cover. 25
13. A chest comprising a body, a cover movably connected to the body, a tray pivoted at its ends to the cover, levers pivotally and removably connected to the ends of the body and pivotally and removably connected to the tray so as to give pivot- 30

14. A chest comprising a body provided in two of its opposite walls with perforations, a hinged cover for the body, a tray pivotally connected at one side of the cover and provided adjacent the other side with perforations, and levers each having its terminals extended in opposite directions and forming trunnions arranged in the aforesaid perforations of the body and the tray, each of said levers being provided at one end with a head forming a stop to retain such trunnion in its respective perforation against movement in one direction and the trunnion when moved in the opposite direction being adapted to be withdrawn through the perforation so as to remove the respective lever from connection with the body and the tray. 80
15. A chest comprising a body provided in two of its opposite walls with perforations, a hinged cover for the body, a tray pivotally connected at one side to the cover and provided adjacent the other side with perforations, and levers each having its terminals extended in opposite directions and forming trunnions arranged in the aforesaid perforations of the body and the tray, each of said levers being of resilient material and bent intermediate of its ends and having trunnions each being provided at one end with a head forming a stop to retain such trunnion in its respective perforation against movement in one direction and having the trunnion at the opposite end of the respective lever sprung into the respective perforation and each lever when its headed trunnion is moved in the opposite direction from that aforesaid being adapted to be withdrawn through the perforation when the sprung trunnion is removed from its perforation so as to thereby remove the respective levers from connection with the body and the tray. 100
